Charles M. Marmick
Design for Shoe
Patented May 30, 1848.

No 183

Des. 183

Charles W. Warnick, Philadelphia, Penn^a,
Letters Patent N° 183, dated May 30th
1848

The schedule referred to in these letters patent and making part of the same.

To all whom it may concern:

Be it known that C^r Charles W. Warwick of the County of Philadelphia State of Pennsylvania, have invented or produced a new cast iron ornamental wood stone called a nine plate stone, and I do hereby declare that the annexed drawing is a full and exact description of the same.

Your petitioner claims to be the original inventor or producer of the design and ornamental part of said nine plate stone.
